UNITED STATES PATENT OFFICE.

GEORGE H. JENKINS, OF OAK PARK, ILLINOIS.

BINDING FOR BOOKS AND METHOD OF EFFECTUATING THE SAME.

1,189,825.

Specification of Letters Patent.

Patented July 4, 1916.

Application filed August 8, 1914. Serial No. 855,881.

To all whom it may concern:

Be it known that I, GEORGE H. JENKINS, a citizen of the United States, residing at Oak Park, in the county of Cook and State 5 of Illinois, have invented certain new and useful Improvements in Binding for Books and Methods of Effectuating the Same, of which the following is a specification.

This invention relates to a method for 10 binding together loose leaves into permanent book form, and is particularly adapted to be practised by persons unskilled in the book binding art by the use of previously prepared materials supplied for the purpose.

15 A further object of the invention is to so bind the loose leaves into book form as to obviate the requirement for the use of machines, implements, or other accessories of an expensive or complicated nature and at 20 the same time afford means which may be employed by unskilled persons in the production of a book binding which is neat, secure, durable, and inexpensive, thereby enabling office employees or others to bind together 25 office records in permanent book form without the necessity for sending such records or other loose leaf material to a book binding establishment.

In the drawings: Figure 1 is a perspective view of a stack of leaves between two covers in position ready to be bound; Fig. 2 is a view of a section of string or cord, the surface being prepared with an adhesive coating; Fig. 3 is a view turned to show both 35 sides of a flexible reinforcing strip, the surfaces of which are coated with an adhesive; Fig. 4 is a cross section of a reinforcing member, the surfaces of which are also coated with an adhesive; Fig. 5 is a view of 40 a modified form of reinforcing member shaped to provide an arch, otherwise similar to Fig. 4; Fig. 6 is a view of the outer layer of material used to cover the book back, the edges being turned substantially in the 45 position occupied during use; and Fig. 7 is a fragmentary view in cross section, enlarged, showing the constituent parts of my binding in relative operative positions.

It will be understood that while my invention 50 has reference to book binding in general it has particular adaptability to the

binding of so-called loose leaf records etc., in which the pages are initially used for current work, and ultimately for reference work. As many volumes of such records are 55 commonly filed away by offices and business houses, it is very desirable that a method of binding such records in permanent form be devised which is simple, cheap, and expeditious to carry into effect. Such is the form 60 and method of binding herein disclosed.

In practising the invention a quantity of leaves 8 are first arranged in proper form after which provision is made for securing the superposed rear edges of the leaves together by first forming in such edges a series of inwardly extending saw-cuts or slots 9, although it is not strictly essential that the cuts in the leaves be in slotted form, since in some instances registering perforations 70 may be employed for the purpose. After the slots or perforations are formed the leaves are secured together by inserting sections of string, cord, or other binding material 10, which in the case of slots may be 75 easily inserted by laying them in the open slots without the necessity of threading them through the leaves. It is preferred to have the sections of string, cord or other binding matter supplied to the user with a coating of glue or the like thereon as indicated at 10^a in Fig. 2, and it is preferred that the glue or the like should be of such a nature as to be rendered adhesive by moistening or immersing in water immediately prior to the 85 time when it is intended for use. The strings, cords, or other binding materials are preferably of a length to project beyond the book leaves so as to be turned down and overlie the outer faces of the book covers 11 90 which are preferably of relatively stiff and indestructible material. After the leaves and covers have been bound together in the manner specified a previously glued relatively flexible inner binding strip 12 is moistened to soften the glue or like material thereon and then applied and pressed against the edges of the leaves and covers to adhere against the individual leaves and this strip is turned or flexed down to overlie 95 the covers and cover and conceal the projecting ends of the binding strings and to 100

more effectually anchor such strings against accidental withdrawal. In order to render the book binding stiff and permanent, a reinforcing strip 13 is next applied which strip is preferably supplied to the user with a coating of glue or the like on each of its surfaces and such glue or like material is of a nature which may be easily softened and rendered adhesive by an application of moisture or by immersion in liquid such as water. The reinforcing strip is formed of card-board, straw-board or similar material and the application of the glue or like material not only serves to afford the necessary adhesive medium but also tends to stiffen and strengthen the reinforcing strip as to best serve the purpose intended. The binding is completed by the application of a covering or finishing strip 14 of a size to have its edges flex down and overlie the rear edges of the covers, and this finishing strip is preferably formed of canvas or other relatively strong and flexible fabric which when supplied to the user has a hardened coating of glue or like material of a nature to be readily softened and rendered adhesive by the application of moisture.

From the foregoing description it will be apparent that with the materials described the unskilled user can easily and economically bind the loose leaves into book form without the necessity of employing appliances or instruments of a complex nature and that the materials are preferably prepared for application with only the necessity of moistening the glue on the various materials to render it adhesive. In practice the user will simply have to moisten the several parts and apply them in the necessary sequence or order to build up the book binding, although it should be understood that the sequence of the operations is not necessarily of the essence of the invention since it is conceivable that substantially the same result might be obtained by performing the operations in other than what might be termed the normal or regular order. The principal feature of the invention, however, resides in the use of prearranged materials adapted first to secure the leaves together against displacement, second, to provide a reinforcement against the breaking or mutilation of the binding, and third, in providing a cover or finish for protecting the binding and rendering it neat and attractive in appearance.

If desired, a reinforcing strip having a curved back portion, such as that shown in Fig. 5 may be substituted in place of the plain strip shown in Fig. 7, in which case the book, when completed, will be provided with a rounded or arched back surface instead of a flat surface. In such case, however, the same principles will be used in the preparation of the binding, and the only

difference will be in the appearance of the completed book.

I claim:

1. The method of binding between slotted or punched covers loose leaves which are correspondingly slotted or punched adjacent one edge thereof, which consists in arranging the leaves between the covers in book form with the slots or punchings in register, inserting sections of binding material through the slots or punchings of the leaves, moistening a strip of material previously coated with glue to render the glue adhesive, applying said strip over the slotted or punched edges of the leaves, adhering a relatively stiff strip of reinforcing material to the flexible material to stiffen the book binding, and completing the book binding by moistening a finishing strip previously coated with glue to render the glue adhesive, and applying the said finishing strip in position to overlie the reinforcing strip and the adjoining edges of the covers. 75 80 85

2. The method of binding between slotted or punched covers loose leaves which are correspondingly slotted or punched adjacent one edge thereof, which consists in arranging the leaves between the covers in book form with the slots or punchings in register, moistening strips of string previously coated with glue to render the glue adhesive, inserting said strips of string through the slots or punchings of the leaves, moistening a strip of flexible material previously coated with glue to render the glue adhesive, applying said strip over said slotted or punched edges of the leaves, adhering a relatively stiff reinforcing strip of material to the flexible material to stiffen the book binding, and completing the book 100 105 binding by moistening a finishing strip previously coated with glue to render the glue adhesive, and applying the said finishing strip in position to overlie the reinforcing strip and the adjacent edges of the covers. 110

3. The method of binding between slotted or punched covers loose leaves which are correspondingly slotted or punched adjacent one edge thereof, which consists in arranging the leaves between the covers in book 115 form with the slots or punchings in register, inserting sections of binding material through the slots or punchings of the leaves, and completing the book binding by moistening a finishing strip previously coated with glue to render the glue adhesive, and applying the said strip over the slotted or punched edges of the leaves and the adjacent edges of the covers. 120

4. The method of binding between slotted or punched covers loose leaves which are correspondingly slotted or punched adjacent one edge thereof, which consists in arranging the leaves between the covers in book form with the slots or punchings in 125 130

register, moistening strips of string previously coated with glue to render the glue adhesive, inserting said strips of string through the slots or punchings of the leaves, 5 and completing the book binding by moistening a finishing strip previously coated with glue to render the glue adhesive, and

applying the said strip over the slotted or punched edges of the leaves and the adjacent edges of the covers.

GEORGE H. JENKINS.
